UNITED STATES PATENT OFFICE.

ANNE E. AGNEW, OF SEATTLE, WASHINGTON.

DESIGN FOR A CANDLE.

Application filed April 21, 1927. Serial No. 21,661. Term of patent 7 years.

To all whom it may concern:

Be it known that I, ANNE E. AGNEW, a citizen of the United States, residing at Seattle, in the county of King and State of Washington, have invented a new, original, and ornamental Design for Candles, of which the following is a specification, reference being had to the accompanying drawings, forming a part thereof.

In the drawings the figure is a view in elevation of a candle embodying my design.

I claim:

The ornamental design for a candle as shown.

ANNE E. AGNEW.
